US00D913426S

(12) **United States Design Patent** (10) Patent No.: **US D913,426 S**
(45) Date of Patent: **** Mar. 16, 2021**

(54) **FAUCET**

(71) Applicant: **DELTA FAUCET COMPANY**,
Indianapolis, IN (US)

(72) Inventor: **Thad Eads**, Urbana, IN (US)

(73) Assignee: **DELTA FAUCET COMPANY**,
Indianapolis, IN (US)

(**) Term: **15 Years**

(21) Appl. No.: **29/679,868**

(22) Filed: **Feb. 11, 2019**

(51) LOC (13) Cl. **23-01**

(52) U.S. Cl.

USPC **D23/238**

(58) **Field of Classification Search**

USPC D23/238-242, 254, 255, 257
